UNITED STATES PATENT OFFICE

JOHN PIERCE, OF SOUTHBURY, CONNECTICUT

TAG

Application filed April 16, 1929. Serial No. 355,445.

This invention relates to an improved tag having a string attached thereto and has for its main object the provision at a low cost for manufacture of a new article of manufacture consisting of a tag and string attached together in such manner as to minimize the danger of tearing the tag when strains are imposed therebetween.

With the above objects in view my invention consists in a tag characterized by having a string-receiving slit formed therein and a string having a portion extending through the said slit from one face of the tag to the other and gripped between the opposed walls of the said slit.

In the accompanying drawings:

Fig. 1 is a detached face view of a tag to which a string is to be attached;

Fig. 2 is a broken view of a piece of string designed to be attached to the tag shown in Fig. 1;

Fig. 3 is a face view of the tag with the string positioned thereover, preparatory to forcing the same laterally through the tag;

Fig. 4 is a schematic sectional view showing a simple form of apparatus for carrying out the manufacturing of my improved tag; the parts being shown in the positions due them preparatory to forcing the string through the tag from one face to the other and applying adhesive to the said string;

Fig. 5 is a view corresponding to Fig. 4 but showing the parts in the positions due them after the string has been forced through the tag and adhesive has been applied to the pushed-through portion of the said string;

Fig. 6 is a face view of a tag having a string attached to it;

Fig. 7 is a corresponding view but looking toward the opposite face of the tag;

Fig. 8 is a sectional view taken on the line 8-8 of Fig. 6;

Fig. 9 is a similar view taken on the line 9-9 of Fig. 6;

Fig. 10 is a perspective view of a series of tags connected together by a single string; and

Fig. 11 is a view corresponding to Fig. 9 but showing a modification in which the end

of the string is pushed entirely through the tag.

In carrying out my invention as herein shown, I position over one face of a tag 15 a string 16, as shown in Figs. 3 and 4 of the drawings, and position both of the same upon a dial-plate 17 of an automatic machine of any approved type. The said dial-plate is preferably formed with a shallow recess 18 to receive and locate the tag 15 and is formed also with a clearance-slot 19 intersecting the said recess near one end and leading downward therefrom, as clearly shown in Figs. 4 and 5 of the drawings.

With the tag and string positioned as shown in Fig. 4 of the drawings, I cause the blade 20 of a punch 21 to move downward and engage the said string between its ends and force the same through the tag in looped form, as shown in Fig. 5 of the drawings, thereby forming in the said tag a slit 22, the opposed walls of which recover sufficiently, after the withdrawal of the blade 20, to pinch the string between them, as clearly shown in Fig. 8 of the drawings.

After the string has been forced through the tag, as above described, I apply to the pushed-through portion 23 of the string a small amount of adhesive, by means of a finger 24, which latter is normally immersed in a bath of glue or other adhesive 25 contained in a tank 26. The said finger offsets from a lever 27 hung upon a pivot 28 and having an arm 29 extending outwardly over the edge of the tank 26 and by means of which the finger 24 may be operated to engage its upper end with the pushed-through portion 23 of the string by any approved operating mechanism which will preferably be timed to bring the said finger 24 into action shortly after the punch 21 has forced the string through the tag.

The application of adhesive to the string 16, as above described, serves to stiffen and solidify the pushed-through portion 23 thereof to such an extent that it is converted into a relatively-rigid bulbous anchor which effectively resists any normal strains tending to pull the string back through the slit 22. In instances where the tag 15 is made of suffi-

ciently tough material, it has been found unnecessary to apply adhesive as above described, but I prefer to so do as a safety measure.

5 Forcing the string through the tags in the manner above described in looped form is especially suitable to manufacturing processes in which it is desired to have a group of tags connected together, as shown in Fig. 10, so that they may be severed at the time of use as required.

10 As shown in Fig. 11 of the drawings, it is feasible to force the end of the string through the tag and still provide a strong connection, though I prefer the looped form first described, since it provides an added area of string for gripping engagement by the opposed walls of the slit 22.

15 In certain instances, where the nature of the tag material is such that it does not possess the proper resiliency to properly recover its original flat form adjacent the slit 22 after the forcing through of the string, it is obvious that rollers or other pressure devices may be employed to insure the recovery of the material of the tag to a sufficient degree to grip the string properly.

20 It is obvious without further illustration that if desired the string may be forced through a given tag at several different points in the event that extra security of attachment is desired.

25 While I have described the forming of the slit 22 in the tag by forcing the string there-through, it is obvious that the tag may be initially provided with a slit before the punch 21 is brought into action to force the string through the tag as described.

30 The improved tag described herein is not only low in cost but is superior, in many respects, to the stringed tags of the prior art and especially so as regards neatness and the strength of the connection between the tag and string.

35 I claim:

1. A new article of manufacture, comprising a tag having a string-receiving slit formed therein and a string having a looped portion extending through the said slit from one face of the said tag to the other and gripped between the opposed walls of the said slit.

40 2. A new article of manufacture, comprising a tag having a string-receiving opening formed therein and a string having a portion extending through the said opening from the front face of the tag to the rear face thereof, upon which latter face it is exposed, and adhesive applied to the exposed portion of the said string to stiffen the fibers thereof to form an anchor for preventing the withdrawal of the string from the said opening.

45 In testimony whereof, I have signed this specification.

JOHN PIERCE.
